HOISTING INDICATOR

John Charwinsky, New York, N. Y.

Application June 8, 1945, Serial No. 598,354

1 Claim. (Cl. 294—1)

(Granted under the act of March 3, 1883, as
amended April 30, 1928; 370 O. G. 757)

1

This invention relates to indicators and more particularly to apparatus for ascertaining the correct alignment of hoisting devices, especially when said hoisting devices are making sensitive lifts of heavy objects.

In the lifting of large and heavy objects out of their jackets such as, for example, the lifting of turbine rotors from their casings, it is necessary to accurately center the crane before a lifting force is applied to said heavy objects. It is apparent that should a lifting force be applied to the crane without the axis of said crane passing through the axis of the turbine rotor or other object lifted by the crane, a side thrust by the rotor upon its casing will result, said thrust being of sufficient force to damage either the turbine rotor or the casing, perhaps both.

Previous to this invention, the lifting of an object from its casing was done by trial and error, the load being lifted slightly several times until a balanced load at the end of the hook of the crane was sensed by the crane operator. When the crane operator felt satisfied that the load he was lifting was balanced, he applied the necessary lifting force to hoist the load out of its jacket.

It is an object of this invention to provide means to increase the accuracy in aligning lifting cranes.

A further object is to make said means for aligning lifting cranes visible from any position by an observer.

Further objects and advantages of this invention, as well as its construction, arrangement and operation, will be apparent from the following description and claim in connection with the accompanying drawing, in which the single figure is a front view of a lifting assembly showing an embodiment of this invention.

Referring to the figure there is shown a crane 10 consisting of a hook, block and cable. The hook portion consists of a pair of hook arms 11, a safety clamp 12 which rests on the tips 13 of said arms 11 to safeguard against slippage of a line from said arms 11, said clamp 12 riding on the shaft 14 of the hook.

The shaft 14 is contiguous with an enlarged portion or head 15, said head 15 being secured by bolts 16 and nuts 17 to a framework 18. A block 19 is similarly secured to the top portion of the framework 14, cables 20 girdling said block 19, the cables 20 being attached to lifting means (not shown).

Near the foot of said framework 18 is a rectangular band 21 which serves to reenforce the framework 18. This band 21 has indicating

2

marks approximately in the center of each side of said band 21. A similar band 23 reenforces the framework 18 near its top but has plumb bars 24 depending from the centers of the front and rear sides of said band 23. Plumb bars 25 depend from offset blocks 26 that are secured to the left and right face of crane block 19 so that the plumb bars 25 are free to move in an arc without interference from nuts 27.

10 The plumb bars 24 and 25 are secured to their respective supports by means of a ball and socket or equivalent universal suspension joint 28 to prevent binding of said plumb bars 24 and 25 against their supports.

15 In operation, the arms 11 of the crane's hook are secured to an object that is to be lifted out of a surrounding jacket. Sufficient tension is applied to the cables 20 in order to barely lift the object from its surrounding jacket. If the crane

20 block should be tilted when said body is thus hoisted, the block bars 24 and 25 will swing out of registration with their respective center line marks 22. Since the plumb bars 24 and 25 are suspended from supports that are at right angles

25 to each other, any tilting about a horizontal plane will be registered. The cables 20 are then adjusted, adjustment being made according to the amount of swing of said plumb bars 24 and 25 away from registration with their respective center lines 22. These initial hoists can be quickly

30 determined by an observer at the ground so that the time involved in determining the proper cable adjustment for a balanced load prior to applying the final hoisting force that will lift a body from its surrounding jacket will be considerably diminished.

35 This invention removes the guesswork in hoisting operations. Moreover, by aiding in the accurate balancing of a load prior to lifting said load, it can prevent damage to sensitive portions on the surface of very valuable heavy equipment.

To further prevent undue swing of the pendulums 24 and 25, guard blocks (not shown) can be secured to the framework 18 to the right and left of said pendulums 24 and 25. These guard blocks will prevent undue swing of the pendulums 24 and 25, thus hastening the lining up of the said pendulums with their respective center lines.

50 It is to be understood that various modifications and changes may be made in this invention without departing from the spirit and scope thereof as set forth in the appended claim.

55 The invention described herein may be manufactured and used by or for the Government of

the United States of America for governmental purposes without the payment of any royalties thereon or therefor.

What is claimed:

In a hoisting apparatus, a vertically disposed framework, hook means secured to the foot of said framework, adjustable hoisting means secured to the top of said framework, reenforcing

bands girdling said framework, indicating markings on the lower reenforcing band, freely rotatable plumb bars universally connected to and depending from said framework, said bars swinging relative to said indicating markings to register the verticality of said framework.

JOHN CHARWINSKY.
